UNITED STATES PATENT OFFICE

2,532,604

AMPOULE HOLDING RACK

Theodore J. Carski, Baltimore, Md., assignor to
 Baltimore Biological Laboratory, Baltimore,
 Md., a corporation of Maryland

Application June 18, 1947, Serial No. 755,329

3 Claims. (Cl. 211—74)

1

This invention relates to a rack for ampoules and similar containers.

An object of the invention is to provide a simple and inexpensive rack for supporting a plurality of ampoules, or similar containers having a neck relatively smaller in diameter than the body thereof, while various operations are performed such as washing, sterilizing, filling, sealing, etc.

An embodiment of the invention is illustrated in the accompanying drawings in which:

Fig. 1 is an inverted side elevation of a rack containing a few ampoules of various sizes and shapes, the rack being in the locked position,

Fig. 2 is an end elevation of a rack in the loading and unloading position with one of the ampoules being in place in the rack,

Fig. 3 is a perspective view of a rack in the loading and unloading position,

Fig. 4 is a perspective of a locked rack in the upright position for filling or sealing the ampoules, and

Fig. 5 is a transverse vertical section taken along the line of 5—5 of Fig. 4.

As appears in the drawings, the rack consists of two relatively movable parts which may be made of any suitable material such as plastic, water-resistant paper board, wood, or preferably a light metal or alloy and by any suitable method of fabrication, for instance by simply bending and shaping sheet metal. A channel 5 is rotatably mounted on a U-shaped frame or support member 6 by pivot pins 7 and is locked in inverted position as shown in Figs. 1 and 4 by friction lock 8. The middle portion or web 9 of the channel 5 is provided with a plurality of openings or holes 10 which are illustrated as being circular but may be of any other suitable shape for receiving the smaller or neck portions of the containers. The spacing of the holes 10 will depend upon their size and the size of the bodies of the containers, the only requirement being that they shall be sufficiently large to receive the necks of the containers, sufficiently small to prevent passage of the bodies of the containers and sufficiently spaced to permit the containers to rest side by side in the rack.

The ends of the channel are closed by tabs 14 which may be merely bent over extensions of the portion of the channel. The tabs 14 serve for attaching the channel 5 to the support member 6 by means of the pivot pins 7.

Side portions 20 of the channel 5 may be of any suitable width and serve not only to strengthen or stiffen the channel but also to provide lateral

support for the containers, i. e. to support the containers in alignment. The same effect might be had by other means. Instead of a channel, a bar of rectangular or square transverse section would accomplish the same purpose if provided with properly proportioned holes.

The side portions also may be plane but preferably are corrugated as illustrated to provide inwardly projecting ridges 19 between the holes to support the containers longitudinally and vertically of the channel and parallel to each other.

The support member 6 is constructed of sheet metal strip or other suitable material of light weight, such as was recommended above for construction of the channel member. The base portion 15 of the support member is made flat and of sufficient width to provide a steady base when the holder is placed on a plane surface for the operation of filling and sealing the ampoules, etc. 15 Along one edge of the base portion 15 is disposed a side flange 16, the ends of which side are adjacent the upright end portions 17. The flange 16 is preferably formed by merely bending up an extended edge of the base of the support. The flange 16 may be dispensed with if all containers to be carried by the rack are of a sufficient size to be positively retained in the rack by means of a close fit between the sides 20 of the channel. However, it is preferable to incorporate a flange 20 in the construction of the rack, since it will serve to steady and retain any containers which are so small as to have a large amount of play or clearance in between the sides 20 of the channel member. The uprights 17 of the support member 30 are constructed of sufficient length so that they will extend up past the level of the tip of the longest of the ampoules 12. These uprights then serve to a certain degree to protect the necks of ampoules from being inadvertently struck as the rack is moved about. In addition, the top edges 18 of the uprights are cut to lie in the same horizontal plane and are thus suitable as legs upon which the holder may be placed if it be desired 35 to support the ampoules in an inverted position for drainage, etc., as illustrated in Fig. 1.

When an empty rack is to be loaded with ampoules, the channel 5 is rotated on its longitudinal axis until the open side of the channel is uppermost and the web of the channel containing the holes is at the bottom. In this position, the channel is upside down with respect to its normal inverted position. The ampoules are then placed "neck-down" in the holes by directing the neck of each ampoule downwardly through a hole until the shoulder of the am-

ampoule rests against the periphery of the hole in which it is placed. Due to the presence of the side walls of the channel and the corrugation or crimp in the sidewalls, each ampoule will rest safely in this position until all ampoules have been placed in the rack.

To lock the ampoules in place, it is only necessary to grasp the channel and rotate the support member with respect to the channel until the base portion of the support member is directly over the bottoms of the ampoules. It is obvious that the channel member cannot be rotated in order to arrive at the locked position, since the ampoules are free to fall from the channel until such time as the rack has been placed in the normal locking position, e. g. the base portion of the support member is in position adjacent the bottoms of the ampoules.

Since the flange 16 will not clear the bottom of the ampoules when the support member as illustrated in Fig. 3 is rotated in a counter-clockwise direction to arrive at the locked position, it is necessary that the support as viewed in Fig. 3 always be rotated in a clockwise direction to arrive at the locked position, and in a counter-clockwise direction to unlock the rack for freeing and removing the ampoules.

Once a filled rack of the proper size with respect to the ampoules to be supported has been set in the locked position, there is no possibility of the ampoules falling out, and the rack may be held at any angle or moved about violently without fear of losing any of the ampoules.

When it is desired to remove the ampoules, the rack is inverted in order that the ampoules will not drop out when the device is unlocked. The support member is then rotated until there is sufficient clearance for removal of the ampoules, and the ampoules are removed by drawing them up through the retaining holes until each ampoule neck is clear of the channel.

Ampoule holding racks of my construction may be made in various sizes and shapes to accommodate ampoules of different sizes and shapes. That is to say, it is within keeping with my invention to vary: (a) the horizontal position on the uprights at which the pivot pins and thus the channel is mounted, (b) the dimensions of the support, (c) the size of the channel, (d) the diameter and shape of the holes in the web, (e) the nature and extent of the corrugations or ridges on the side portions of the channel, and (f) the distance between adjacent holes. However, it is to be noted that any particular rack constructed according to my invention is adapted to receive containers varying within a limited size range. Any given container will be safely supported and retained by a given rack so long as the following conditions generally are met: (1) the container neck will pass through a hole in the web, (2) the shoulder of the container at some point has a diameter greater than the diameter of the hole, (3) the diameter of the upper portion of the body of the container is less than the clearance between the oppositely disposed sides of the channel, and (4) the distance between the base of the container and the point at which its shoulder contacts the periphery of the hole is no greater than the distance between the upper surface of the base portion of the support member and the bottom surface of the web of the channel.

It will be observed that it is unnecessary for the shoulder of an ampoule to remain in contact with the periphery of the hole. As long as either the neck of the ampoule passes through the hole

a sufficient distance while the base of the ampoule is resting on the base portion of the support member, or there is sufficiently limited play of the ampoule between the side portions of the channel while the bottom of the ampoule is resting on the base portion of the support member, then there is no danger of having the ampoule fall from a rack which is in the locked position.

Also, it may be said that any number of ampoules equal to or less than the capacity of the rack normally can be safely carried in the rack. That is to say, if only one ampoule has been placed in a rack, that ampoule will be secure in its position while the rack is locked particularly if the rack has corrugated channel sides, it being only necessary that the ampoule be of proper size for the particular rack.

The rack comprising my invention is adapted for use and association with other equipment employed in the handling and packaging of biologicals. For instance, my rack is admirably suited for presenting a plurality of ampoules to the ampoule sealing device disclosed in copending U. S. design application of John H. Brewer, Serial No. D135,736 filed December 24, 1946, now Patent No. Des. 153,584. Also, I may conveniently fill a number of ampoules by employing box lots of ampoule holding racks filled with ampoules in conjunction with the filler track disclosed in U. S. patent application of John H. Brewer, Serial No. 733,700 filed March 10, 1947.

Thus it will be appreciated by those familiar with the problems encountered in the handling and packaging of biologicals in small lots, that the ampoule holding rack of the present invention is a device which though easily and inexpensively constructed, is extremely useful as a means for safely and rapidly handling and conveying a plurality of ampoules through the steps of washing, sterilizing, filling, sealing, storing, etc.

I claim:

1. An ampoule holding rack comprising a support member and a channel member, said support member consisting of a base portion having a side portion adjacent and perpendicular to and longitudinally coextensive with said base portion, an upright portion adjacent each end of said base portion, said channel member having each of its ends associated with one of said upright portions by means of a pivot pin whereby said channel member is rotatable about an axis parallel to its central longitudinal axis, at least one upright portion being provided with locking means adapted by cooperation with an adjacent end portion of said channel member to hinder rotation of said channel member, the middle portion of said channel member being provided along its central longitudinal axis with a plurality of openings and the side portions of said channel member being provided with corrugations providing a plurality of parallel ridges extending perpendicular to the long axis of the channel adapted to hold ampoules in alignment.

2. A rack for a plurality of ampoules or the like containers of a substantially common size having bodies and necks extending from the upper ends of said bodies of smaller diameters than said bodies, said rack comprising a support and an elongated inverted channel having a web and sides, said support having an elongated base, an upturned side flange substantially coextensive therewith, and an upright adjacent each end thereof, said uprights supporting said channel

at its ends by means whereby said channel is rotatable on a longitudinal axis, the web of said channel being provided along its length with a plurality of substantially aligned openings on centers spaced by distances at least as large as and approximating the diameters of said ampoule bodies, said openings having effective diameters of an order which will pass the necks of said ampoules without passing the bodies thereof, the sides of said channel being spaced apart substantially the width of said ampoule bodies and adapted to receive said bodies therebetween, and said base being substantially parallel to and spaced apart from said web by a distance substantially equal to the body length of said ampoules, whereby with the rack inverted and the support rotated until the base is offset from a position overlying the channel, the ampoules may be inserted downwardly and neck foremost into the openings to be held with a minimum of play with substantial portions of their bodies between the sides of the channel and whereby the ampoules subsequently may be made secure against dislodgement by rotation of the support

back into its original position overlying the channel so that with the rack in upright position the base supports the ampoules and the flange on the base acts as a stop for the bottom of the ampoules to limit tilting motion of the base and channel in one direction.

3. A rack as defined in claim 2 wherein the channel member has at least one of its side portions provided with corrugations providing a plurality of parallel ridges extending perpendicular to the long axis of the channel adapted to hold ampoules in alignment.
